SOAP RACK

Adolph Backstrom, Hempstead, N. Y.

Application February 9, 1940, Serial No. 318,039

3 Claims. (Cl. 45—28)

This invention is concerned with improvements in soap trays, and a particular object thereof is to provide a collapsible tray or rack which may, when collapsed, be readily packed flat in a small envelope, and which when assembled is adapted to rest upon a lavatory or conventional soap dish.

A further object of the invention is to provide an elevated soap rack adapted to so support the soap that it may dry thoroughly after use without becoming gummy, due to water absorption, on its lower surface as frequently occurs when soap cakes are deposited flat upon a lavatory surface or closed soap dish.

A further object is to provide a soap rack which holds a cake of soap in a tilted position so that surplus water thereon may drain to a corner of the cake, thus avoiding the nuisance of having the soap soft on one side and hard on the other.

A further object of the invention is to provide means by which water erosion of a soap cake is minimized to the end that greater economies in the use of soap may be effected.

A further object is to provide a collapsible soap rack which may be readily fabricated from plastic materials at a very low price and which accordingly may be considered as a semi-disposable item, although when made from suitable materials the rack will have indefinite life.

Still another object is to provide a soap rack which will readily accommodate either a full size cake of soap or one which has become rather small through frequent use.

Further objects and advantages of the invention will become apparent in reading the detailed description below in connection with the drawing, in which:

Fig. 1 is a perspective view of an assembled soap rack;

Fig. 2 is a section on the line 2—2 of Fig. 1;

Fig. 3 is a plan of the coupling element for the rack;

Fig. 4 is an end view of one of the rack elements;

Fig. 5 is a perspective elevation showing how the rack may be packaged when collapsed;

Fig. 6 is an end view of an alternative embodiment of the invention, indicating how a cake of soap is disposed thereon, and

Fig. 7 is a perspective view of the coupling element for the alternative arrangement.

The rack comprises a plurality of similar flat members 10, each provided with a flat bottom edge 11 which may, if desired, have bosses at 55

the ends thereof, and an inclined thickened top edge 12 terminating in an abutment 13 at its lower end. The thickened top edge is shown in Fig. 2. Preferably, four such members 10 are disposed in parallel spaced relation and are secured to one another by a coupling member 14 which comprises a flat strip, as shown in Fig. 3, having slots 15 extending part way across the width of the strip. The members 10 are slotted at 16 whereby the members 10 may be assembled on the member 14 with the slots 15 and 16 respectively embracing portions of the sides of the members 14 and 10. The fit of the members with respect to their slots is intended to be quite close so that the members are held in their proper relation by frictional engagement when once assembled. The member 14 may be disposed with its flat surface either horizontal, as shown, or angled with respect to a horizontal plane, and preferably the strip lies rearwardly with respect to notches 17 between the inclined edges 12 and the abutments 13. When a cake of soap is placed across the several members 10 it will, of course, be inclined with respect to the horizontal and water thereon will flow along the surface of the soap to the lowermost corner thereof whence it may drip on to the supporting surface, whatever it may be. By disposing the strip 14 in horizontally spaced relation relative to the soap cake, the drip from the lowermost corner of the soap will not impinge upon the member 14.

It will be appreciated that the several elements 10 and 14 are flat in themselves and thus they may easily be packaged in a flat envelope as indicated in Fig. 5, thus affording a small and compact package which may readily be placed in luggage or on sales counters in a minimum space. To afford economy of material used in the device, the wider portions of the members 10 may be formed with openings 18, which openings also allow for the insertion of the member 14 when the members 10 are being assembled thereon.

In Figs. 6 and 7, an alternate arrangement is shown wherein the vertical members 20 have lower and upper edges 21 and 22 respectively, after the manner of the first embodiment. Through each member 20 a slot 23 is formed, the central portion of the slot comprising a circular hole 24. A coupling member 25, shown in Fig. 7, comprises a central rod 26 having flat portions 27 spaced therealong and projecting from opposite sides thereof, the spacing between the flat portions 27 being the same as the thick-

ness of the members 20. Accordingly, the rod 26 may be passed through the hole 24 of each member 20, and as each such member lies opposite a space between the flat portions 27, the members 20 and 25 may be rotated a quarter turn relative to one another by which they are securely retained in proper position. The top edge 22 may have an integral abutment 28 formed thereon to act as a stop when the members 20 and 25 are turned relative to each other.

As indicated above, the several elements of the device are preferably made from plastics, although they might likewise be made from metals or other non-metallic material. Fig. 6 indicates how a cake of soap may be placed upon the rack, and Fig. 7 additionally shows small flat portions 29 at the ends of the rod 26 by which the end members 20 are retained in assembled relation. Any suitable number of members 10 or 20 may be used, although it is deemed that four is an adequate number to provide support for a cake of soap of either full dimension or reduced dimension resulting from use, the plurality of members 10 or 20 allowing for the support of the soap as it reduces in size.

While I have described my invention in detail in its present preferred embodiment, it will be obvious to those skilled in the art, after understanding my invention, that various changes and modifications may be made therein without departing from the spirit or scope thereof. I aim in the appended claims to cover all such modifications and changes.

I claim as my invention:

1. A demountable rack for a soap cake comprising a plurality of more than two similar upright flat elements each having a base edge, a top edge inclined throughout a major part at an angle of substantially 20° with respect to the base edge and inclined throughout a minor part to make substantially a right angle with the major part, said minor part starting at that end of the major part which is closest to the base edge, front and rear edges respectively joining the base edge with the ends of the minor and major parts of the top edge; said flat elements each having an opening therein part of which is in the form of a slot; and a cross element formed from a rectangular strip having spaced slots along a longer side thereof, said strip passing through the openings of the several flat elements and having the elements passed into the spaced slots, the cross element being also passed into the slots of the flat elements.

2. A demountable rack for a soap cake comprising a plurality of more than two similar upright flat elements each having a base edge, a top edge inclined throughout a major part at an angle of substantially 20° with respect to the base edge and inclined throughout a minor part to make substantially a right angle with the major part, said minor part starting at that end of the major part which is closest to the base edge, front and rear edges respectively joining the base edge with the ends of the minor and major parts of the top edge; said flat elements each having an opening therein part of which is in the form of a slot; and a cross element formed from a rectangular strip having spaced slots along a longer side thereof, said strip passing through the openings of the several flat elements and having the elements passed into the spaced slots, the cross element being also passed into the slots of the flat elements, successive slots in the rectangular strip, and hence said flat elements, being spaced apart a distance which is substantially less than half of the length of a normal new soap cake but the end flat elements being spaced apart a distance which is substantially equal to the length of a normal new soap cake, whereby two or more of said flat elements serve to support a soap cake whether new or reduced in size due to use.
3. A demountable rack for a soap cake comprising a plurality of more than two similar upright flat elements each having a base edge, a top edge inclined throughout a major part at an angle of substantially 20° with respect to the base edge and inclined throughout a minor part to make substantially a right angle with the major part, said minor part starting at that end of the major part which is closest to the base edge, front and rear edges respectively joining the base edge with the ends of the minor and major parts of the top edge; said flat elements each having an opening therein part of which is in the form of a slot; and a cross element formed from a rectangular strip having spaced slots along a longer side thereof, said strip passing through the openings of the several flat elements and having the elements passed into the spaced slots, the cross element being also passed into the slots of the flat elements, the whole top edge of each of said upright flat elements being formed as a rounded bead of greater thickness than the balance of the element.

ADOLPH BACKSTROM.
